CLAIM

The ornamental design for an electroacoustic transducer, as shown and described.

DESCRIPTION

FIG. 1 is a perspective view of the top, front and left side of an electroacoustic transducer showing my new design;

FIG. 2 is a front elevational view thereof, the rear elevational view being a mirror image thereof;

FIG. 3 is a top plan view thereof;

FIG. 4 is a left side elevational view thereof, the right side elevational view being a mirror image thereof;

FIG. 5 is a bottom plan view thereof;

FIG. 6 is the 6—6 sectional view of FIG. 2;

FIG. 7 is the 7—7 sectional view of FIG. 5;

FIG. 8 is the 8—8 sectional view of FIG. 5; and,

FIG. 9 is a 9—9 sectional view of FIG. 5.
